W. LINDHOLM

THERAPY LAMP

Filed Nov. 9, 1923

Patented Aug. 10, 1926.

1,595,303

UNITED STATES PATENT OFFICE.

WILLIAM LINDHOLM, OF BRIDGEPORT, CONNECTICUT.

Therapy Lamp.

Application filed November 9, 1923. Serial No. 673,742.

This invention relates to therapy lamps, and especially to the reflectors for this type of lamp and the means for mounting the lamp within the reflector.

- 5 It has for an object to provide an improved and simplified construction for the shade or reflector for this type of lamps which may be quickly and easily assembled or disassembled and in which there is means 10 for providing a thorough circulation of air over all the surfaces of the shade or reflector in any position in which it may be used, so as to always maintain the shade or reflector cool and prevent undue heating.
- 15 It is also an object of the invention to provide an improved and simplified construction of the means for mounting the socket for the lamp within the shade or reflector.
- 20 It is a still further object of the invention to provide an improved means for retaining the lamp in an inclined position if it is desired to use it for directing rays laterally to the side of a patient.
- 25 With the foregoing and other objects in view, I have devised the construction illustrated in the accompanying drawing, forming a part of this specification, similar reference characters being employed throughout the various figures to indicate corresponding elements. In this drawing,
- Fig. 1 is a partial section and partial side elevation of my improved shade or reflector.
- Fig. 2 is a side elevation thereof looking from the left of Fig. 1.
- Fig. 3 is a detailed section through the securing means at the top of the reflector.
- Fig. 4 is a bottom plan view of a portion of the reflector, and
- 40 Fig. 5 is a side elevation showing the method of use of the device for retaining the lamp in an inclined position.

I have indicated at 10 any suitable type of incandescent lamp which is used for therapeutic purposes. This lamp has threaded engagement in a socket 11 which is preferably composed of insulating material, such as porcelain, enclosing the usual contacts to which the lead wires 12 enclosed in the cord 13 are connected in the usual manner to conduct electric current to the lamp from any suitable source of supply. The internal construction of this socket is not illustrated as it forms no part of my present invention.

55 The lamp is enclosed by a shade or casing 14 which is dome shaped and open at the

bottom for the exit of the light rays from the lamp. The lower edge may be finished in various ways but is preferably rolled outwardly to form a bead 15. Carried within 60 this casing is an auxiliary reflector 16 which is also dome shaped. It is of less length as compared with its diameter than the outer reflector or casing 14. This reflector also embraces the lamp, but is placed above the 65 enlarged portion of the lamp so as to reflect the rays downwardly. It is provided in the top thereof with an opening 17 through which the upper portion of the lamp extends, and this opening is sufficiently 70 larger than the lamp to leave a free passage for cooling air. To increase the flow of cooling air the reflector is also preferably provided with a row of openings 18 about the opening 17. This reflector flares outwardly at its lower end and is preferably rolled over at 19 to form a bead resting against the inner surface of the casing 14, and is mounted in position by suitable screws 20. For the purpose of increasing 75 the cooling effect and to insure flow of air over the inner surface of the outer member 14 in all positions in which the reflector may be used, means is provided at the lower outer edge of the reflector 16 for passage of air from below to above this reflector and over the inner surface of the outer member 14. Various means may be used to provide passage for this air, as for example, mounting the reflector spaced from the outer member, but I prefer to provide a series 80 of notches 21 in the edge of the reflector and extending throughout its periphery. Above this auxiliary reflector 16 the outer member 14 is provided with a series of openings 85 for exit of the cooling air, as for instance a series of upright slots 22.

At the upper end of the device is a block 23, preferably a metal casting, which carries the shade or reflector and the lamp. This block is provided with a transverse slot 24 leading from the upper end thereof and an opening 25 leading from the upper end for entrance of the cord 13. Adjacent its inner end this block is provided with a female thread 26 to receive the externally threaded projection 27 carried by the socket 11. At its lower end this block has a cylindrical flange 28 to project into the upper end of the insert 29 and to which it is connected by any suitable means, such as screws 30. The block also preferably has a flange

31 to form a stop shoulder for the upper end of the insert and to give a finished appearance. The insert flares outwardly at its lower end, as shown at 32, and is overlapped 5 with the upper end of the shade or casing 14 to which it is secured by suitable means, such as screws 33. This insert is also provided with a series of upright slots 34 for exit of cooling air.

10 At its upper end the block 23 is provided with ears 35 through which extend clamping screws 36 by which the opposite sides of the block may be clamped against the cord 13 to relieve the connection of the lead wires to 15 the contacts in the socket 11 of the weight of the lamp and reflector.

It is at times desirable that the lamp should be used in an inclined position in order to project the rays at an angle to the 20 vertical, as when it is desired to project the rays to the side of a patient. To allow for this I have provided bosses 37 on opposite sides of the block 23 and mount thereon a pivoted holding device 38. This device is 25 preferably made of a flat strip of metal bent to substantially U-shape with the opposite sides 39 embracing the block and bearing against the bosses 37, and passing through these arms and the block is a bolt 40 with 30 a thumb nut 41. This provides a pivotal connection between the holding element and the block, and also provides means for clamping the element to the block in different positions. The remainder of the holding 35 device is shaped so as to lie closely adjacent the outer surface of the casing 14 when not in use as shown in Fig. 1. By loosening the nut 41 the holding device may be swung about its pivot to any position desired and 40 then clamped therein by means of the thumb nut. The method of using this device to hold the lamp in an inclined position is shown in Fig. 5. The holder is swung so that the cord 13 will rest in the seat formed 45 in the free end of the holder by the connection 42 joining the sides and where the holder is clamped in this position it will react with the cord to hold the lamp inclined, as shown in Fig. 5.

50 It will be apparent from the foregoing description that the mounting and reflector for the lamp are very simple in construction involving a small number of parts which may be quickly and easily assembled and disassembled. The three sections of the 55 reflector, 14, 23 and 29 may be easily disconnected by removing the screws 30 and 33. I consider my improved means of mounting the lamp socket 11 within the reflector also of importance. By providing a female thread 26 in the block 23 and providing an externally threaded projection 27 on the socket it will be obvious the socket may be easily screwed in position or unscrewed 60 therefrom, and that these operations may be 65

performed without in any way disassembling the reflector. This construction is also cheaper to manufacture.

From an inspection of Fig. 3 it will be seen that, as the bolt 40 passes transversely 70 through the passage for the cord 13, this cord is bent laterally to one side of the bolt, and this bend coacts with the bolt to provide an additional means of taking part of the strain of the weight of the lamp and reflector from the connections of the lead wires to the contacts in the socket.

It will also be apparent that when the lamp and reflector are held in an inclined position there can be no pocket for dead air 80 formed at the juncture of the reflector 16 and the member 14, the notches 21 allowing any air which might collect in this pocket to pass through and to the exit slots 22. Thus there is always a flow of cooling air over 85 the inner surface of members 14 and 16, preventing any overheating.

Having thus set forth the nature of my invention, what I claim is:

1. In a therapy lamp, a dome shaped casing 90 enclosing the lamp and open at its top and bottom, a tubular insert connected with the casing at its top and forming a continuation thereof and provided with air exit openings in its side walls, a block secured to the other end of the insert and provided with a longitudinal passage, a socket for the lamp carried by the block within the insert, lead wires extending through said passage to the socket, and an inner dome shaped reflector enclosing the lamp within the casing and mounted above the bottom of the casing, said reflector being provided with an air outlet opening at the top thereof about the lamp and outwardly extending projections at the lower end thereof to space it from the casing and allow cooling air to flow over the inner surface of said casing.

2. In a therapy lamp, a shade or casing enclosing the lamp, a one piece block to which the shade is connected having a transverse slot extending from its outer end, a lamp socket carried by the block, said block having a longitudinal opening therethrough, lead wires extending through said opening 100 to the socket, and means for clamping the slit portion of the block to the lead wires.

3. In a therapy lamp, a one piece block having a longitudinal opening extending 110 therethrough and provided with a transverse slot leading from the outer end thereof, a lamp socket secured to the inner end of the block, lead wires passing through the block from the outer end to the socket, and means for clamping the opposite sides of the slit portion of the block against the lead wires.

4. In a therapy lamp, a block having a longitudinal passage extending therethrough and having side walls providing clamping portions, a reflector secured to said block, 120

said block being provided with a female thread, a socket enclosed by the reflector having lamp contacts and provided with an externally threaded projection adapted for engagement with the threads of the block, lead wires extending through said block to the socket and means for clamping said clamping portions to the lead wires.

5. In a therapy lamp, a block provided with a longitudinal passage and a transverse slot leading from its outer end, a reflector secured to the block, said block being provided with a female thread, a lamp socket enclosed by the reflector and having an externally threaded projection adapted for engagement with the threads of the block, lead wires extending through said passage to the socket, and means for clamping the opposite sides of the block to the lead wires.

20 6. In a therapy lamp, a block provided with a longitudinal passage and walls forming clamping portions, a reflector, a tubular insert secured to the block and the reflector, said block being provided with a female thread, a lamp socket enclosed by the insert and provided with an externally threaded projection adapted for engagement with the threads of the block, said reflector and insert being provided with exit openings for cooling air lead wires extending through the passage in the block to the socket, and means for clamping said clamping portions against the lead wires.

35 7. In a therapy lamp, a block, a reflector secured to the block, a lamp within the reflector, lead wires extending through the block to the lamp, a holding device having spaced side elements straddling and pivoted to the block and adapted to swing on its piv-

ot to and from engagement with the lead wires and adapted to coact therewith to hold the lamp and reflector in an inclined position, and means for securing the holding device in adjusted positions.

8. In a therapy lamp, a block having a longitudinal passage, a reflector carried by the block, a lamp socket carried by the block within the reflector and having lamp contacts, lead wires extending through the passage to the socket and connected with the contacts, a holding device pivoted to the block, said pivot comprising a bolt extending transversely through the passage in the block in position to cause the lead wires to bend laterally, and means for clamping the holding device in adjusted positions, said device adapted to swing to and from engagement with the lead wires and to coact therewith to hold the lamp and reflector in inclined positions.

9. In a therapy lamp, a block, a reflector carried by the block, a lamp enclosed by the reflector, lead wires extending through the block to supply current for the lamp, a substantially U-shaped holding device arranged with the side members thereof embracing the block, a pivot bolt extending through the side members and the block, and a nut on the bolt for clamping the device in adjusted positions, the portion of the device connecting the side members adapted to engage a side of the lead wires and coact therewith to hold the lamp and reflector in inclined positions.

In testimony whereof I affix my signature.

WILLIAM LINDHOLM.
